UNITED STATES PATENT OFFICE.

OSCAR F. FORSBERG, OF YONKERS, NEW YORK, ASSIGNOR TO WESTERN ELECTRIC COMPANY, OF NEW YORK, N. Y., A CORPORATION OF ILLINOIS.

ELECTROMAGNET.

1,117,485.

Specification of Letters Patent. Patented Nov. 17, 1914.

Application filed August 31, 1911. Serial No. 647,039.

To all whom it may concern:

Be it known that I, OSCAR F. FORSBERG, citizen of the United States, residing at Yonkers, in the county of Westchester and State of New York, have invented a certain new and useful Improvement in Electromagnets, of which the following is a full, clear, concise, and exact description.

This invention relates to electromagnets and its principal object is to provide such a structure wherein mechanical work, under loads of extreme variation, may be performed efficiently and positively.

To the above end a structure is provided wherein the operating element, after a preliminary predetermined movement to an intermediate position, picks up its load, and wherein the momentum of the operating element gained during the preliminary movement, supplemented by an increased magnetic attraction, insures positive operation against the greatest mechanical resistance.

This invention will be fully understood from the following description taken in connection with the accompanying drawing in which,—

Figure 1 is an elevation, partly in section, showing the magnet with its armature connected to do mechanical work, as in the control of a pay station coin chute or coin collecting apparatus; Figs. 2, 3 and 4 show the construction and arrangement of the magnet poles, the armature mounting and coöperating parts.

The foundation of the structure comprises a yoke *k* which may be and preferably is of soft iron, so as to form an efficient section of the magnetic circuit for the electromagnetic elements. Secured to the yoke *k* are two coils *b* formed on soft iron cores *c* in the usual manner. The ends of cores *c* opposite those adjacent the yoke *k* have cut-away portions forming pole faces *d* which materially increase the efficiency of the electromagnet, as will be hereinafter explained. Near the pole faces *d* the cores *c* are interconnected by and support a bridge *y*, which is provided with two upturned projections *5* between and to which the armature structure, to be hereinafter described, is pivotally mounted.

The armature structure comprises a support *10* of non-magnetic metal provided with downwardly projecting ears *11*. The

ears *11* are perforated or indented to receive the points of trunnion screws *12* thus forming a pivotal bearing, about which the support *10* may be rotated. Support *10* is also provided with elongated openings *13*, *14* and *15*. The longer axes of openings *13* and *15* are in a line substantially perpendicular to the axial line of support *10*, while the axis of opening *15* is parallel to the axial line of support *10*, for a purpose which will now be explained. An armature *a* is adjustably held to the support *10* by clamping screws *77*, which project therethrough and thread into the armature *a*. An adjusting screw *78* with an eccentrically formed head, which rests within the opening *14*, also threads into the armature *a*. It will, therefore, be readily understood that when screws *77* are loosened, the turning of adjusting screw *78* will move the armature *a* in a direction transverse to the axis of its support *10*. The tightening of screws *77* will hold the armature firmly in position. By these means the location of the armature *a*, relative to the pole faces *d*, may be adjusted at will to compensate for any variations of the magnetic forces exerted by the two coils *b*.

The trunnion screws *12* pivotally support a plate *80*, through the agency of perforations or indentations in its downwardly projecting ears *81*. Plate *80* is further provided, on each side of its axial line, with downwardly extending projections *85* which are adapted to be engaged by the armature *a*. The location of the perforations in ears *81* and the lengths of projections *85* are so determined that armature *a*, when attracted to rotate in either direction, may move freely through a small angle before engaging one of the projections *85*. Plate *80* is likewise supplied at each end with a downwardly projecting arm *95*, adapted when the armature *a* is rotated to engage the bridge *y*, to limit such rotary movement. One of the ears *81* of plate *80* is elongated and forked, as shown, and may be suitably connected to any desired mechanical movement. In the preferred embodiment disclosed the fork of elongated ear *81* engages *105* and is adapted to move a rod *g* of a coin-distributing mechanism *f*.

Means are provided to normally hold the armature in a neutral position relative to the pole faces *d*, and to return the armature to *110*

normal position after being displaced by the magnetic attraction of coils *b*. This mechanism comprises the two independently movable levers 82 and 83, likewise pivotally mounted on trunnion screws 12. Each of these levers is provided with a small projection 84 adapted to be engaged by the plate 80 and thereby communicate the motion of armature *a* to either lever 82 or 83, depending upon the direction of rotation of the armature. Thus when the armature moves in a clockwise direction, it carries with it only the lever 82, while if the rotation of the armature is in the reverse direction, only lever 83 will be moved thereby. The construction, whereby a small projection, such as 84, communicates motion from plate 80 to either lever 82 or 83, reduces the sliding friction, while the armature is being rotated, and is therefore a factor in increasing the efficiency of the entire structure. Levers 82 and 83 are provided with downwardly extending arms 91 and 92 respectively, which normally rest against the tops 25 of the cores *c* because of the tension of springs 89 which are connected at one end to the framework and at the other end to levers 82 and 83, as shown. It is therefore readily apparent that armature *a* is normally yieldingly held in a neutral position relative to the pole faces *d*, and is positively and accurately returned to this position after it has been displaced and the coils *b* have become deenergized.

30 An arm 17, extending from plate 80, may be employed to control the engagement of contact springs, such as 18 and 19, which are joined to current-carrying leads 20, and a permanent magnet *p* may be secured to the 35 yoke *k* and extend beside the coils *b*, as shown.

In operation the coils *b* may be energized to deflect the armature *a* in either direction. Upon such energization the preliminary 40 movement of armature *a*, due to the formation of pole faces *d*, causes a relatively great decrease in the air-gap between the depressed end of armature *a* and the coöperating pole face *d*, and a corresponding increase 45 in the air-gap between the other end of the armature and its coöperating pole face. Thus, the magnetic attraction is greatly augmented and the operative force exerted by the armature is materially increased. Due 50 to the space between the projections 85 and armature *a*, the armature makes this preliminary movement and so increases the effect of the magnetic field, as above explained, before the load joined to ear 81 is 55 picked up. When armature *a* engages one of the projections 85, plate 80 rotates about trunnion screws 12, resulting in a rotary movement of one of the levers 82 or 83 and

the operation of contact springs 18 and 19 by means of projection 17. The movement 65 of plate 80 and consequently of armature *a* and lever 82 or 83 is regulated and checked by the engagement of one of the arms 91 or 92 with the yoke *y*. When the current ceases to flow through coils *b*, springs 89 70 return the displaced lever 82 or 83 until its arm 91 or 92 engages the pole of its corresponding core *c*, whereupon the apparatus is again at normal.

I claim:

1. An electromagnet comprising a pair of electromagnetic elements, a bridge therebetween, an armature pivoted to said bridge, a pair of independently movable levers supported on the armature pivots and adapted 80 to be singly and selectively actuated by said armature, and means for communicating motion from said armature to said levers and to limit the movement thereof.

2. An electromagnet comprising a pair of 85 coils, a bridge therefor, an armature pivoted to said bridge, a plate supported on the armature pivots and movable by said armature, and a pair of spring tensioned levers supported on the armature pivots and adapted 90 to gradually increase the load on said armature during its movement.

3. An electromagnet comprising a pair of 95 coils, a bridge therefor, an armature pivoted to said bridge, a plate supported on the 100 armature pivots and movable by said armature after a preliminary movement thereof, two levers likewise supported on the armature pivots and movable by said armature, and a retractile spring for each of said 100 levers.

4. An electromagnet comprising a pair of 105 coils, a bridge therefor, a pivoted armature for said coils, a plate supported on the armature pivots and spaced from said armature 110 to be moved thereby only after a preliminary movement thereof, and means carried by said plate to limit the movement of said armature by engagement with said bridge.

5. An electromagnet comprising a pair of 110 coils, a pivoted armature therefor, a plate supported on the armature pivots and spaced from said armature to be moved thereby only after a preliminary movement thereof 115 to limit the movement of said armature, and a pair of spring tensioned levers likewise supported on the armature pivots and movable by said armature and adapted to gradually increase the load carried thereby.

In witness whereof, I hereunto subscribe 120 my name this 30th day of August A. D., 1911.

OSCAR F. FORSBERG.
